UNITED STATES PATENT OFFICE.

LOUIS W. BRUEGGEMAN, OF MILWAUKEE, WISCONSIN.

SECTIONAL PORTIÈRE.

1,230,271.

Specification of Letters Patent. Patented June 19, 1917.

Application filed April 3, 1915. Serial No. 18,948.

To all whom it may concern:

Be it known that I, LOUIS W. BRUEGGEMAN, a citizen of the United States, residing at Milwaukee, in the county of Milwaukee and State of Wisconsin, have invented certain new and useful Improvements in Sectional Portières, of which the following is a specification.

This invention relates to portière structures and is more specifically concerned with the provision of a sectionally extensible portière or curtain support.

As a principal object, it is contemplated by this invention to provide a portière structure which shall be capable of adjustment for positioning in various sized doors, archways, windows and the like by means of sectional inserts.

It is a coördinate object to provide a portière structure of the type set forth which may be immediately augmented or reduced in width without the use of tools in fulfilling the adjustment features of this invention.

25 A further object is to provide slidable means whereby the portières or curtains may be hung or as readily removed, while it is also an important aim to render a completed structure artistically uniform in such manner as to leave no suspicion of its sectional character.

The above and additional objects which will become apparent as this explanatory description proceeds are accomplished by such means as are illustrated in the accompanying drawings, described in the following specification and then more particularly pointed out in the claims which are appended hereto and form a part of this application.

With reference to the drawings, wherein there is illustrated the preferred embodiment of this invention as it is reduced to practice, and throughout the several views 45 of which like character of references designate similar parts:

Figure 1 is an elevation of an interior doorway which is spanned by the sectional portière of this invention,

50 Fig. 2 is an enlarged vertical sectional view taken through the portière structure showing the manner of securing the sections,

Figs. 3 and 4 are transverse sectional views taken on the respective lines 3—3 and 4—4 of Fig. 2,

Fig. 5 is a sectional view taken through one of the portière or curtain fabric strips, and

Fig. 6 is a perspective detail of the hanger bracket in which the structure is removably supported.

In the embodiment of this invention, the complete portière is made up of a number of separate portions, each portion comprising a section 10 or 11, means carried by the sections for connecting one to another and for supporting the portière in position, and depending flexible strips 35 hanging from the sections and forming the curtain part 70 of the portière, as illustrated in the drawings, there is employed a pair of main sections 10 which may be joined to and spaced by any number of intermediate sections 11 according to the width of the door, arch- 75 way or window which it is desired to span. Considering the section 11 as one unit of the sectional portière, it will be seen that the main sections 10 are illustrated as having a length of four such units but it is to be understood that these main sections may bear 80 any ratio to the single unit or may even be dispensed with when the entire structure is built up of a number of jointed single units.

By reference to Figs. 2, and 3, it will be 85 seen that each of the main sections includes a pair of parallel frame members 12 and 13, each of which is formed intermediately with a mortise groove 14. The frame members of each of the main sections are separated and 90 maintained in spaced alignment by means of rectangular metallic sheathing 15 which is seated firmly in each mortise groove 14 at the extremity of each of these main sections 10. Through one of these hollow sheathings 95 there is slidable the telescoping metallic sheath 16 which has extending therethrough flush with the outer end but projecting beyond the inner end thereof a beam 17 preferably constructed of wood in order to receive 100 the enlarged handle staple 18 which is adapted to project upwardly from the slidable beam above the upper surface of the frames 12 and 13 and between the same as is best illustrated in Fig. 3. This handle 18 serves 105 to limit outward movement of the sheathing beam 17 by abutting the fixed sheathing 15 while the portion of this beam extensible beyond the edge of the frame members is adapted to be received by the door or window 110 bracket 19 formed with the central aperture 20 of such shape as to accommodate the

said projecting end. Any desirable fastening means may extend through the apertures 21 of this bracket in order to secure the same permanently to the inner face of the door or window frame 22.

5 The foregoing describes how one end of each of the sections 10 is supported. Their inner ends spaced by one or more sections 11 are supported by the latter through the 10 medium of lateral connections. The sheathing 15 of one of the sections 10, accordingly, supports a fixed male sheath 23 adapted to extend beyond the said inner end in a manner differentiable from the telescopic sheath 15 only by reason of its stationary position. A short beam 24 is also used with this fixed sheath and serves a purpose to be herein-after more fully set forth.

Each of the sections 11 is similarly formed 20 with a pair of side members 25 and 26 differing from the members 12 and 13 only in the matter of length, that of the sections 11 being the unit length of the sectional portière. A lining or sheathing 27 also lines 25 a mortise groove 28 in continuance of the groove 14 in order to receive the extended end of the male sheath 23. This section is also formed with a male sheath 29 to project beyond its opposite end and to perform a similar function to the sheath 23 when being received within the inner end of the remaining main section 10.

These male sheaths insure support of the 30 intermediate sections and of the inner ends 35 of the main sections but latches 30 must be employed to prevent lateral displacement of the sections, such latches being pivoted to the respective frames 13 and 25 as indicated by the numeral 31 to coöperate with keepers 40 32 carried on the appropriate extremity of the intermediate section and the right hand main section. Each of these latches which 45 may take the form illustrated or any desirable shape projects above the adjacent upper edges of the respective section frame members and may be formed with notches 33 whereby their manual release is facilitated from engagement with the keepers 32, the filling beam 24 and the section sheathing 50 27 serving to support these latches in their disengaged positions.

From the foregoing it will be clearly understood in what manner the sectional portières are supported and adjusted to fit 55 doorways, windows or interior arches of various sizes, it being readily understood that the described section 11 is a type of all the intermediate sections while the main sections 10 may bear any desired length-ratio through these intermediate sections. Upon reference to Fig. 1, it will be apparent 60 that each of the sections 10 is subdivided by scored lines 34 in order to present an outward appearance simulating the single unit sections 11 rendering the addition or re-

moval of one such unit section unnoticeable by an inspection of the entire portière structure.

It will be obvious that where the unit idea of a sectional portière structure is carried out in the manner disclosed in the foregoing that the portières or curtains supported by such structure must conform in a similarly unified manner. For this reason the specific disclosure of the portière structure presented by this invention is believed to be dependent upon the underlying basis furnished by the sectional portière or curtain structure previously disclosed.

Accordingly, the portières or curtains have been designed upon the multiplicity unit system being made of a number of separate portions each of which portions comprises a section 10 or 11 and one or more depending flexible strips 35 hanging therefrom. The section 11 serves as the unit width of one of said separate portions and supports a single strip 35. The sections 10 are shown as having a width of four such units and sustaining four flexible strips 35. Sections of two, three, five or more unit widths will carry strips in proportion to their widths. As shown in the drawings, the strips 35 are made of cloth or other fabric of any ornamental material such as 80 silk, velvet, plush, wool or cotton and the like and are fastened between the members 12 and 13 of the sections 10 and between the similar members 25 and 26 of the unit sections 11 through the medium of bolts, 85 brads, tacks or other fasteners 36 which are preferably positioned in the center of the lower portion of each of the real or simulated sections as is clearly shown in Fig. 1. These strips are of a width somewhat less 90 than those of the sections and depend therefrom in various lengths supporting panels 37 which are secured front and back to these dependent strips and are preferably formed of a thin wood or veneer stained to fit with the decorative key-note of the particular 95 room or rooms in which they are placed. As shown these shields or panels and their supporting strips do not obstruct the central entrant portion of the door or window 100 frame 22 to any considerable extent and being light and pivotally mounted by the fasteners 36 may be easily brushed aside at the passage of a person although always returning to their uniform position as illustrated. It will be understood that the assemblage of a portière structure in the manner disclosed will carry out the sectional unit idea in every detail and the number 105 of units 11 positioned between end sections 110 10 will in no particular destroy the artistic uniformity of the entire device.

While in the foregoing however, there has thus been illustrated in the drawings and described in the specification such combina- 115 120 125 130

tion and arrangement of elements as constitute the preferred embodiment of this invention, it is desired to emphasize the fact that such minor changes in the matters of proportion and degree may be made in later adaptations of this device as shall fall within the scope of the appended claims.

What is claimed is:

1. A portière comprising a plurality of 10 separable portions, each portion including an independent rigid section, said sections adapted to be connected one to another endwise for self-support and to extend across a window or door frame, and means projecting from the extremities of the connected sections for supporting the portière in position.

2. A portière comprising end portions and an intermediate portion, each portion 20 including a rigid section, the ends of which sections are connected one to another endwise to extend across a window or door frame and form a unitary article, means projecting from the extremities of said connected portion 25 sections for supporting the same, and locking means between the sections.

3. A portière comprising a plurality of 30 separable portions, each portion including a rigid section, which sections are adapted to be connected one to another endwise to extend across a window or door opening, each of said sections being formed of spaced parallel bars and a tubular member sustained between said parallel bars at each 35 end thereof, a telescopic support for connecting the adjacent ends of said sections, and projecting members at the extremities of the connected sections for supporting the same.

4. A portière comprising end sections and an intermediate section separably connected together to extend across a door or window opening, each of said sections being formed of two parallel strips connected together, each strip having a facing groove 40 to seat a telescopic connecting member for the adjacent section, fastening means between the sections for holding them securely after being connected, and means projecting from the ends of the connected sections 45 for sustaining the portière and depending strips.

5. In a portière structure, end sections, 50 manually operative slidable means for supporting one end of each section, each of said sections being formed to represent a number of assembled unit sections, intermediate unit sections, projecting means vertically supporting adjacent sections, latch means 55 preventing lateral displacement of the adjacent sections, and dependent portière strips secured to each of said real or simulated unit sections extending uniform distances from said unit sections and varying 60 distances from said simulated sections.

6. In a portière structure, end sections including spaced frame members subdivided on their faces to represent unit sections, intermediate unit sections each including mating spaced frame members, means slidable 70 between said members at one end of each of said first sections to removably support the same, means projecting similarly from adjacent sections to vertically support said intermediate sections, and latch means coacting between said adjacent sections to prevent lateral displacement thereof.

7. In a portière structure, end sections including spaced frame members subdivided on their faces to represent unit sections, intermediate unit sections each including mating spaced frame members, means slidable 75 between said members at one end of each of said first sections to removably support the same, means projecting similarly from adjacent sections to vertically support said intermediate sections, latch means coacting 80 between said adjacent sections to prevent lateral displacement thereof, portière fabric strips depending from each of said real or simulated sections, and decorative panels spaced on each strip.

8. In a portière structure, end sections including spaced frame members provided with facing grooves, the outer faces of said 95 members being scored to represent assembled unit sections, intermediate unit sections including mating frame members similarly grooved, a metallic sheathing at each end of said end sections and lining the groove of 100 said unit sections, means slidable through the sheathing of one end of each of said first sections to support the structure, and means projecting similarly from adjacent sections to horizontally support said unit 105 sections, keepers carried on adjacent sections, and latches pivoted for manual operation to engage said keepers in preventing lateral displacement of all of said sections.

9. In a portière structure, end sections including spaced frame members provided with facing grooves, the outer faces of said members being scored to represent assembled unit sections, intermediate unit sections including mating frame members similarly grooved, a metallic sheathing at each 110 end of said end sections and lining the groove of said unit sections, means slidable through the sheathing of one end of each of said first sections to support the structure, 115 and means projecting similarly from adjacent sections to horizontally support said unit sections, keepers carried on adjacent sections, latches pivoted for manual operation to engage said keepers in preventing lateral displacement of all of said sections, portière fabric strips depending from each of said real or simulated sections, and decorative panels spaced on each strip.

10. In a portière structure, the combina- 130

tion with brackets provided with central openings, and supported by a door or window frame, of end sections including spaced frame members provided with facing 5 grooves, said members having their outer faces subdivided by scoring to represent assembled unit sections, sheathing spacing said members at each end of said sections and in said grooves, a slideable sheath through said sheathing at one end of each of said sections, intermediate unit sections, sheaths projecting from adjacent sections to support said intermediate sections, keepers carried by adjacent sections, latches pivoted for 10 manual operation to releasably engage said 15

keepers, handle means carried by said slideable means to move the latter into engagement with the apertures of respective brackets, portière fabric strips pivoted centrally of each real or simulated unit section depending therefrom uniformly for said intermediate sections and variously for said end sections, and decorative shields carried spacedly upon said strips. 20

In testimony whereof I affix my signature 25 in presence of two witnesses.

LOUIS W. BRUEGGEMAN.
